UNITED STATES PATENT OFFICE.

FREDRICK L. JACOBS, OF DETROIT, MICHIGAN.

METAL LADDER.

Application filed May 8, 1922. Serial No. 559,256.

To all whom it may concern:

Be it known that I, FREDRICK L. JACOBS, a citizen of the United States, residing at Detroit, in the county of Wayne and State 5 of Michigan, have invented a new and useful Metal Ladder, of which the following is a specification.

This invention relates to ladders and more particularly relates to ladders of metallic 10 construction.

It is the object of the invention to provide a metal ladder of very light yet strong construction, having a novel structural formation and union between its rungs and the tie 15 connections between the uprights or side rails of the ladder.

In attaining this object, the invention contemplates the use of metal tubing to form both the rungs and side rails, and the provision of tie rods passing through certain 20 of the rungs, and having headed extremities engaging in recesses formed by indenting the side rails, the bosses formed by the indentations being utilized to support and reinforce 25 the rungs by entering the ends thereof.

In the accompanying drawing,

Fig. 1 is a front view of the improved ladder.

Fig. 2 is an enlarged longitudinal section 30 of a portion of the ladder.

Fig. 3 is a cross section on a plane intersecting one of the rungs.

In these views the reference character 1 designates the uprights or side rails, and 2 35 the rungs of the ladder, said parts being formed of steel tubing, preferably seamless. It is preferred to employ rungs of circular cross section and side rails of a cross section elongated transversely of the rungs. As 40 shown, the front and rear faces of the side rails are rounded, while the inner and outer faces thereof are flat. Thus the side rails present smooth continuous surfaces for engagement by the hands of a person using 45 the ladder. The rungs 2 are passed snugly through openings in the inner wall of the side rails and abut interiorly against the outer walls thereof. Through certain of said rungs, for example alternate ones, tie

rods 3 are passed, said rods having terminal 50 heads 4, one of which may be a nut, clamping against the outer faces of the side rails. It is undesirable to so expose said nuts that they may encounter the hands of a person using the ladder. The invention avoids such 55 exposure by indenting the outer walls of the side rails in registration with such of the rungs as enclose tie rods, and locating the heads 4 within the indentations 5. Such 60 location of said heads not only avoids obstructing the exterior faces of the side rails but to some extent houses said heads within the side rails so as to afford some protection 65 against moisture and consequent corrosion.

The interior bosses 6, which are produced by the indentations 5, are utilized to reinforce the extremities of the rungs, said bosses being proportioned to snugly fit into 70 said extremities. Thus the load upon any of the rungs enclosing the tie rods is distributed to both the inner and outer walls of the side rails.

The described location of the tie members within certain of the rungs is further advantageous in that concealment of the tie 75 members is thus effected, so that the latter detract nothing from the appearance of the ladder. Also this location prevents improper use of the tie members as foot rests. It is a desirable feature of the described construction that it permits of a very rapid and 80 secure assembly of the parts and produces a comparatively light and strong ladder having a flush and smooth exterior.

What I claim is:

In a ladder, a tubular side rail having flattened opposite wall portions with an opening in one of said portions and a boss in the other extending toward said opening and forming an indentation exteriorly of 90 the rail, a tubular rung passing through said opening and embracing said boss, and a tie member extending within the rung and having an enlargement within said 95 indentation.

In testimony whereof I sign this specification.

FREDRICK L. JACOBS.
